MARK S. MORSE, OF OAKLAND, CALIFORNIA, ASSIGNOR OF TWO-FIFTHS TO J. R. WATSON, JR., OF ALAMEDA, CALIFORNIA.

SIGNALING DEVICE.

1,094,584.

Specification of Letters Patent. Patented Apr. 28, 1914.

Application filed May 11, 1912. Serial No. 696,697.

To all whom it may concern:

Be it known that I, MARK S. MORSE, citizen of the United States, residing at Oakland, in the county of Alameda and State of California, have invented certain new and useful Improvements in Signaling Devices, of which the following is a specification.

My present invention relates to signal systems and instrumentality appertaining thereto, and is particularly adapted for use in connection with railroads where it is usually desirable that the signal device proper be remote from the instrumentality which sets the signal into action.

15 The principal object of my invention is to provide instrumentality disposed in electric conducting means which is set into operation to complete a circuit therethrough, due to the vibrations of some portion of the 20 stationary stock, such as the rails, of a railway, resulting from the passage of some of the rolling stock thereby, the circuit thus completed setting into operation suitable signal mechanism.

25 Further objects of my invention are, to provide a simple and efficient device for completing the electric circuit, and to render the device adjustable so as to be sensitive according to the vibratory qualities of 30 the element to which it is connected.

In the drawings, forming a part of this specification: Figure 1 is a view partly in section and partly in elevation, showing the application of the device embodying my in-

35 vention applied to a rail. Fig. 2 is a transverse vertical sectional view through the casing of the device embodying my invention. Fig. 3 is a diagrammatic view showing the application of the device to a signal system.

40 Similar characters refer to similar parts throughout the views.

Generally speaking, 1 designates a rail of a railway, 2 the circuit control device, and 3 the arm for rigidly securing the said device to said rail.

While I have shown the device as attached to a rail and will hereinafter describe it as being so attached, it is to be understood that the said device may be attached to or 45 supported by any other element, such as trolley wire support, or rail tie, which is in proximity to the place where the action of moving rolling stock is to set the signal or signals into motion, and which is vibrated 50 by the movement of such stock. The said

circuit control device 2 comprises generally, a suitable casing 4, provided with a lid 4'; an insulated base 5, preferably secured by screws 6 to a ledge 7 of said casing; an electro-magnet frame 8, of non-magnetic material; electro-magnets 9; an armature 10 for said magnets; and a vibratable contact arm 11. The electro-magnet frame 8 is preferably provided with standards 12, 13 and 14, the former two supporting the electro-magnets, while the latter carries an adjustable screw 15. The standard 13 is provided with arms 16, which pivotally support the armature holder 10, and arms 17 and 18, the latter of which carries insulated therefrom a contact 19 for co-operation with the said vibratable arm 11. This latter element is carried in an insulated manner by armature holder 10' and projects between the contact 19 and arm 17, normally resting against the latter. The support 10' has an arm 20 passing through an aperture 21 in standard 13, which is adapted to receive a weight 22. By moving this weight farther away from the pivotal point of arm 10', more tension is placed upon vibratable arm 11 against arm 17, or by moving it toward the said pivotal point, the tension is reduced. In other words, by moving the weight 22 farther from the pivotal point of the arm 10', the 55 minimum amplitude of vibration to which the arm 11 will respond is accordingly increased, and by this means adjustment of the relay to the minimum amount of vibration to which it is desired to subject the relay to for operation is obtained. The vibratable arm 11, is, by conductor 23, connected with the coils of electro-magnets 9. As a practical embodiment of my invention, and with particular reference to Fig. 3 of the 60 drawing, an electric generator 24 is provided, one pole of which, by conductor 26, being operatively connected with contact 19, and the other pole, being operatively connected by conductor 25 with the electro-magnets 9. Operatively connected with either conductor, in the drawing that designated 26, I dispose a switch device 27, of any suitable type, and an electro-magnet 28. This electro-magnet 28, when energized, is 65 adapted to draw an armature 29 to contact or complete a circuit through a contact 30. This contact 30 and armature 29 are, by conductors 31 and 32, respectively, connected with an electric generator 33 and in the cir- 70

cuit is disposed a signal device 34, of the audible type, although it is to be understood that a visional signal or an audible signal, other than that shown, of any suitable type, 5 may be used without departing from the spirit of my invention.

With particular reference to the arm 3, as shown in the drawing, it includes a hook 35 to engage over one flange of the rail 1, a 10 strap 36 being secured by nut and bolt 37 and 38, respectively, over the other flange in connection with the arm 3. By this arrangement the vibration imparted to the rail 1 by the rolling stock is transmitted to the 15 device 2, and more particularly to actuate arm 11.

The operation of the device is as follows: When rolling stock passes over the rail or in 20 proximity to the element to which the circuit control device is attached or supported, the arm 11 is vibrated and as soon as amplitude of vibration is sufficient to contact the said arm with contact 19, a circuit is completed through electro-magnets 9 which immediately draws the armature 10 toward it and so retains it with the said arm 11 in 25 engagement with contact 19. Inasmuch as with this position of parts, a continuous circuit is formed through the electro-magnets 30 9, the said armature 10 is rigidly held under influence thereof and likewise, the arm 11 and contact 19 are in engagement. The completed circuit through electro-magnet 28 actuates armature 29 and a circuit is completed through signal device 34, to actuate 35 it. The signal 34 remains active or set, until the switch 27 is opened. Switch 27 is of the normally closed type and preferably located adjacent to the signal 34 so that such 40 signal may readily be rendered inoperative after each passage of the rolling stock.

I claim:

1. The combination with an electrically operated signal system, of a device adapted 45 to be vibrated by movement of rolling stock, including a stationary contact, a vibratable contact for coöperation therewith and normally spaced apart therefrom, electrically actuated means operatively connected with 50 said second mentioned contact adapted to positively hold the same in contact with said first mentioned contact when energized and conducting means between one of said contacts and said electrically actuated means, 55 the other contact and the electrically actuated means being operatively connected in a circuit of said signal system in series with said first-mentioned contact and conducting means, substantially as and for the purpose 60 set forth.

2. The combination with an electrically operated signal system, of a device adapted 65 to be vibrated by movement of rolling stock, including a stationary contact, a vibratable contact for coöperation therewith and nor-

mally spaced apart therefrom, electrically actuated means operatively connected with said second mentioned contact adapted to positively hold the same in contact with said first mentioned contact when energized, conducting means between one of said contacts and said electrically actuated means, mechanism for adjusting the sensitiveness to vibrations of said second mentioned contact, the other contact and said electrically actuated means being operatively connected in a circuit of said signal system in series with said first mentioned contact and conducting means, substantially as and for the purpose set forth. 70 75 80

3. A signal system comprising in combination, a stationary contact, a vibratable contact for coöperation therewith and normally spaced apart therefrom, electrically actuated means operatively connected to said second mentioned contact adapted to hold the same in engagement with said first mentioned contact, conducting means between one of said contacts and said electrically actuated means, an electric generator, conducting means operatively connecting said generator with said first mentioned contact and electrically actuated means, a switch disposed in said second mentioned conducting means, an electro-magnet disposed in 95 said second mentioned conducting means, switching means operated by said electro-magnet, and a signal circuit operatively connected to said switching means, substantially as and for the purpose set forth. 90 100

4. The combination with an electrically operated signal system, of a device adapted to be vibrated by movement of rolling stock, including an electro-magnet, a movable armature therefor, a vibratable arm carried by 105 and insulated from said armature, and electrically connected with said electro-magnet, a contact normally spaced apart from said vibratable arm but in proximity thereto, to be engaged by said arm when vibrated, the 110 relative positioning of said armature, vibratable arm and contact being such that the latter two are held in engagement, when said armature is under the influence of said electro-magnet, and means operatively connecting said contact and electro-magnet with the signal system. 115

5. The combination with an electrically operated signal system, of a device adapted to be vibrated by movement of rolling stock, 120 including an electro-magnet, a movable armature therefor, a vibratable arm carried by and insulated from said armature, and electrically connected with said electro-magnet, means for adjusting the sensitiveness to 125 vibration of said arm, a contact normally spaced apart from said vibratable arm but in proximity thereto, to be engaged by said arm when vibrated, the relative positioning of said armature, vibratable arm and con- 130

tact being such that the latter two are held in engaging relation when said armature is under the influence of said electro-magnet, and means operatively connecting said contact and electro-magnet with the signal system.

6. A control device for signal circuits, comprising in combination, an electro-magnet, a pivotally mounted armature therefor, 10 a vibratable arm carried by said armature and insulated therefrom, means normally limiting movement of said vibratable arm in one direction, a contact for coaction with said vibratable arm and normally spaced apart therefrom, and a conductor between said vibratable arm and electro-magnet, substantially as and for the purpose set forth.
7. A control device for signal circuits, comprising in combination, an electro-magnet, 20 a pivotally mounted armature therefor provided with an arm, a weight movable upon said arm, a vibratable arm carried by said armature and insulated therefrom, means normally limiting movement of said vibratable arm in one direction, a contact for coaction with said vibratable arm and normally spaced therefrom, and a conductor between said vibratable arm and electro-magnet, substantially as and for the purpose set forth.
8. A control device for signal circuits comprising in combination, a base adapted to be attached to a vibratable member, an electric magnet mounted on said base, a pivoted armature for said magnet, an arm attached to said armature and adapted to vibrate in response to the vibration of said member, a vibratable contact arm connected to said armature and insulated therefrom, 30 a contact for coaction with said contact arm mounted on said base, an electrical connection between said contact arm and the winding of said electro-magnet, said vibratable arm being adapted to normally hold said contact arm away from said contact and to move said contact arm against said contact in response to the vibration of said members,

and said electro-magnet being adapted, when energized, to hold said armature in such position as to hold said contact arm 50 against said contact.

9. A control device for signal circuits comprising in combination, an electrical magnet adapted to be attached to a vibratable member, a pivoted armature for said magnet, an arm attached to said armature and adapted to vibrate in response to the vibrations of said member, a contact for coaction with said arm, an electrical connection between said arm and the winding of 60 said electric magnet, and a weight connected to said armature and adjustable with respect to the pivot thereof, said weight being adapted to normally hold said contact arm away from said contact, and being 65 adapted to determine the minimum amplitude of vibrations to which said arm will respond, and said electrical magnet being adapted when energized, to hold said arm against said contact.

10. A signal system comprising in combination, a master circuit, a source of energy connected in said circuit, a normally opened switch, a member adapted to be operated solely by vibration and adapted to close said 75 switch, and means for holding said vibratable member in position to close the switch when the circuit is once closed.

11. A signal system comprising in combination, a master circuit, a source of energy 80 connected in said circuit, a normally opened switch, a member adapted to be operated solely by vibration and adapted to close said switch, means for holding said vibratable member in position to close the switch when 85 the circuit is once closed, and means for adjusting the minimum vibration to which said member will respond.

In testimony whereof I affix my signature in presence of two witnesses.
